(57) **CLAIM**

The ornamental design for a suspension saddle, as shown and described.

DESCRIPTION

FIG. 1 is a perspective view showing the top, front, and right side of a suspension saddle having the inventive design;

FIG. 2 is a front elevational view of the suspension saddle shown in FIG. 1;

FIG. 3 is a top view of the suspension saddle shown in FIG. 1; FIG. 4 is a bottom view of the suspension saddle shown in FIG. 1;

FIG. 5 is a right side elevational view of the suspension saddle shown in FIG. 1;

FIG. 6 is a left side elevational view of the suspension saddle shown in FIG. 1; and,

FIG. 7 is a back elevational view of the suspension saddle shown in FIG. 1.

The broken line showing of portions of a suspension saddle shown in FIGS. 1, 3, 4, and 7 is included for the purpose of illustrating environment and forms no part of the claimed design.
